GAS BURNING RADIANT HEATING UNIT

Harrison D. Sterick, Pittsburgh, Pa.

Application August 19, 1954, Serial No. 450,873

3 Claims. (Cl. 126—92)

This invention relates to a gas heating unit, and more particularly, to a heat intensifier or salamander which may be mounted either overhead, on the side wall, or on the floor of a room; or in a furnace.

An outstanding disadvantage of overhead gas heating units of conventional construction, and similar units for radiant heating, is that a large amount of heat is thrown in the direction of the ceiling or wall, instead of to the central portion of the room where desired. It has been estimated that only about 28 percent of the available heat of a conventional overhead heating unit is thrown downwardly because of the natural tendency for heat to rise from the heating source, even in the presence of reflectors which merely become overheated and allow upward conduction as well as radiation of heat.

An object of my invention is to provide a novel heating unit which will overcome the above-named disadvantages of well-known types of heating units and which will considerably increase the efficiency thereof so that over 70 percent of the heat will be reflected downwardly from an overhead type of heater unit as compared to about 28 percent which is reflected downwardly by conventional overhead units.

Another object of my invention is to provide a gas heating unit which enables considerably greater concentration and more directional reflection of the heat rays emanating from the unit and which substantially eliminates the flow of heat in a direction away from the space to be heated.

A still further object of my invention is to provide a burner and heat intensifier combination which is useful for overhead heaters.

Other objects and advantages of the present invention will become apparent from a study of the following description taken with the accompanying drawing wherein:

Figure 1 is a vertical cross-sectional view of an overhead heating unit embodying the principles of my invention;

Figure 2 is a transverse cross-sectional view taken along line 2—2 of Figure 1; and

Figure 3 is a vertical cross-sectional view of a further modification of an overhead heating unit embodying a plurality of burners.

The steel wool mat 3 of loose, random oriented metallic fibers has the unexpected and amazing quality of reflecting the heat of the burner downwardly and allowing practically no upward escape of the heat to the ceiling. The lower portion of the mat 3 becomes red hot or incandescent and radiates heat downwardly, somewhat like that from the sun, whereas the top portion of mat 3 is relatively cool so that it can be safely touched by the hand. This is because the mat is sufficiently thick and dense so as to intercept substantially all the radiant heat emanating upwardly from the lower surface of the mat and reflect said heat downwardly. In short, the mat acts as an insulator to heat tending to travel in an upward direction and acts as an excellent radiator of heat in a downward direction, thus enabling over 70 percent of

2

the available heat to be reflected downwardly into the room through the spaces between the radially extending portions of burner 1. Mat 3 need not, necessarily, be made of metal but may be made of other fibrous, heat-insulating materials.

Instead of making mat 3 in the form of random oriented metallic or non-metallic fibers, a plurality of layers of screening, preferably metal screening, may be used instead. However, experiments show that such plurality of layers of metal screening has a greater tendency to burn out than a mat of loose, steel wool fibers.

In modifications to be described hereinafter it should be noted that while reference is made to mats of steel wool, that the above-mentioned substitutes may be used instead.

A modified form of overhead or ceiling type of heating unit is shown in Figures 1 and 2 and comprises a burner 1a and a metal screen 6 surrounding it and being upwardly and outwardly flared to provide a support for the steel wool mat 7. A metal shield 8 is supported above mat 7 and has a downwardly dished central portion 8a and a plurality of holes 8b spaced about the periphery thereof to provide a vent ring to allow the escape of gas fumes from the burner. The burner has a horizontal area less than half of that of the open bottom of shield 8. The flames from the burner ports play on the bottom surface only of mat 7, therefore making it red hot and radiating heat downwardly, whereas the upper surface, including the reflector and shield 8, will remain relatively cool and will aid in further reflecting escaping heat in a downward direction.

Figure 3 shows a further modification of the invention embodying a plurality of burners 10, 11 and 12. While three burners are shown, it will be apparent that a smaller or larger number may be used instead. A circular or oval shaped metal screen 13 surrounds and is supported by the burners and provides a vertical support for a mat 14 of steel wool or the like. The metal reflector and shield 15 is similar in construction to shield 8 shown in Figure 1 in that it has a downwardly dished top portion and is provided with a plurality of vent holes 15a which are spaced circularly around the upper portion of the shield. If desired, shield 15 may be replaced by a metallic or non-metallic screen which acts as a backing or support for the steel wool 14. A base 16 is formed of widely spaced radial wires of grid-like formation.

It will be apparent that instead of gas burners, other types of heating units such as oil burners may be substituted.

Thus it will be seen that I have provided a highly efficient gas heating unit which is adapted to reflect heat away from walls or ceilings and thus prevent heat loss in such direction and which enables directional radiation and substantial concentration of heat rays towards the central portion of the room where desired; furthermore I have provided a heat intensifier or salamander which is useful also in stoves mounted on floors, or in furnace heating units; furthermore I have provided heating units wherein a multiple number of burners may be used for either overhead or floor mounted units.

While I have illustrated and described several specific embodiments of my invention, it will be understood that these are by way of illustration only, and that various changes and modifications may be made within the contemplation of my invention and within the scope of the following claims.

I claim:

1. An overhead gas heating unit comprising a gas burner having an upper multi-ported face, a metallic screen extending above and surrounding the flame zone of said burner, a mat of random oriented, fine metallic fibers supported in spaced relationship above said burner

in generally parallel relationship to the face of the burner so that the flames from the burner ports will play only on the lower surface of the mat to make said surface incandescent and radiate heat downwardly and a metallic housing open at its bottom and closed at its top, said housing surrounding said mat and being perforated peripherally adjacent its top to serve as a vent and reflector, whereby said housing is kept relatively cool because of the heat insulating and the downward, heat reflective qualities of the upper portion of said mat, and said burner having a horizontal area less than half that of the open bottom of said housing whereby most of the heat developed is radiated downwardly, exteriorly of the burner and into the space underneath said housing.

2. An overhead gas heating unit comprising a gas burner having an upper multi-ported face, a metallic screen supported by said burner and encircling the flame zone of the burner, a mat of heat resistance, alloy steel wool fibers supported in spaced relationship above said screen and burner in generally parallel relationship to the face of the burner so that the flames from the burner will play only on the lower surface of the mat to make said surface incandescent and radiate heat downwardly, and a metallic housing open at its bottom and substantially closed at its top, said housing surrounding said mat and being perforated at its top to serve as a vent and reflector, whereby said housing is kept relatively cool because of the heat insulating and downward, heat reflective qualities of the upper portion of said mat, and said burner having a horizontal area less than half that of the open bottom of said housing whereby most of the heat developed is radiated downwardly, exteriorly of the burner and into the space underneath said housing.

3. An overhead gas heater comprising a mat of random

4
oriented, stainless steel wool, a metal, heat-reflecting housing closely surrounding the side and top surfaces of said mat, said housing having an open bottom and a vent opening in the top portion thereof, a multi-port gas burner surrounded by said housing and having a plurality of horizontally spaced, ported portions, spaced vertically underneath and confronting only a portion of the lower surface of said mat so that flames emanating from said ported portions will make said lower surface incandescent, 5 said mat being sufficiently thick and dense so as to intercept substantially all the radiant heat emanating upwardly from said lower surface and reflect said heat downwardly, said burner having a horizontal area less than one half that of the open bottom of the housing, 10 whereby most of the heat will be radiated downwardly through the spaces between said horizontally spaced ported portions so as to heat the space below said burner, and means for maintaining the mat, housing and burner in fixed relative position.
